POWDER APPLICATOR

Brown Bolté, Orange, N. J., assignor to Scott & Bowne, Bloomfield, N. J., a corporation of New Jersey

Application May 12, 1937, Serial No. 142,154

4 Claims. (Cl. 128—265)

This invention relates to new and useful improvements in powder applicators particularly of the type employed for applying powder to the interior surfaces or cavities of the body.

- 5 I am aware of the fact that such devices have heretofore been patented, but all such devices with which I am familiar have certain disadvantages which the device of the present invention overcomes.
- 10 It is the primary object of the present invention to improve the construction of such devices in such a manner as to render them more efficient, simple in operation, and of a more sanitary character.
- 15 One serious disadvantage of all such devices with which I am familiar is that the powder is discharged in a single blast-like action instead of a continuous spray or stream, and it is an object of this invention so to construct the device 20 that this serious disadvantage is overcome.

Further, in all such devices with which I am familiar, the powder, although merchandised in closed containers in the form of cartridges which are placed in the device, all such cartridges must 25 have their ends opened or removed before insertion into the device. This requires compression of the charge by the fingers of the user and exposes the powder to contamination.

In the present device the powder is merchandised in closed cartridge-like containers which are placed in the device in their closed position, the cartridges being automatically opened when the device is assembled for use.

Still a further object of the invention resides 35 in a novel form of powder cartridge which lends itself readily to automatic opening after it has been placed in position in the device.

Other objects of the invention will appear as 40 the nature of the invention is better understood, and reference will be had to the following specification and claims and to the accompanying drawing, wherein,

Figure 1 is a view in elevation of a device constructed in accordance with the present invention,

Figure 2 is a fragmentary longitudinal sectional view of the insertible head section of the device, the view being on a slightly enlarged 50 scale,

Figure 3 is a detail sectional view taken substantially on the line 3—3 of Figure 2,

Figure 4 is a fragmentary longitudinal sectional view illustrating the manner in which the 55 device operates,

Figure 5 is a perspective view illustrating the improved powder cartridge,

Figure 6 is a perspective view of the body portion of the cartridge,

Figure 7 is a plan view of the cartridge 5 wrapper, and;

Figure 8 is a detail longitudinal sectional view illustrating a slightly modified form of insertible head.

Referring more particularly to the drawing, 10 the device includes an insertible head 10 from which projects a stem 11, preferably curved, and 12 designates a pressure producing device, preferably in the form of a conventional compressible bulb.

In both of the illustrated forms of the invention the insertible head comprises two members 14 and 16 and the stem 11 is illustrated as an integral extension of the member 14 of the insertible head. The two members 14 and 16 are 20 separably connected together by a threaded connection 18 and each is hollowed out to provide, when threaded together, an insertible head having a cartridge receiving recess 20.

In Figures 5 through 7 of the drawing I have 25 illustrated one form of a new and improved cartridge for use in connection with my device, and I will not proceed to describe the same.

The cartridge consists of a hollow body portion 22 having its ends open and preferably of cylindrical form. This body portion may be formed from any suitable material but I prefer to employ paper, cardboard or some similar material from which to form it. The reference character 24 designates a wrapper for enclosing the cartridge 35 body portion and for closing the ends thereof. This wrapper is of a length sufficient to pass around the cartridge body at least once and of a width greater than the length of the cartridge body to provide portions 26 which may be tucked 40 into the open ends of the body portion to close the same. One end of the wrapper is cut at an angle as at 28 and this end may be provided with a suitable adhesive designated 30.

The hollow cartridge is filled with powder, 45 after which it is enclosed in the wrapper 24, the portions 26 of the wrapper being tucked into the open ends of the cartridge body to form the complete wrapper shown in Figure 5.

It is obvious that if such a cartridge were inserted in an insertible head of ordinary construction, the pressure produced by such a device as the bulb 12 would not be sufficient to effect a discharge of the contents of the cartridge, and I therefore provide means for rupturing the car- 50

tridge wrapper in order that the contents of the cartridge may be discharged by such pressure as the bulb 12 is capable of producing. This means for rupturing the cartridge is so incorporated in 5 the device that the cartridge may be placed in the insertible head before the cartridge has been opened, the rupturing operation being accomplished automatically upon operatively connecting together the two members of the insertible 10 head 10.

The foregoing result is accomplished in the following manner:

The end wall of the recess in the member 14 is so formed as to provide a conical projection 34 15 which extends into the cartridge chamber. This construction provides a shoulder 36 with which the adjacent end of the body portion of the cartridge is adapted to engage when the cartridge is in its operative position. The end of the body 20 portion of the cartridge is forced into engagement with the shoulder 36 by reason of the engagement of the opposite end of the body of the cartridge with a shoulder 38 at the end wall of the recess of the member 16 of the insertible 25 head 10, when the two members 14 and 16 of the insertible head 10 are threaded together.

Threading together of the two members 14 and 16 forces the projection 34 inwardly of the adjacent end of the cartridge, forcing the tucked 30 in portion 26 thereof inwardly of the cartridge to open the end thereof.

The member 16 of the insertible head forms the discharge member thereof and has a discharge passage extending therethrough, the member 14 35 having an inlet passage 40 which leads into the cartridge receptacle 20.

The discharger passage of the member 16 has a contracted neck portion 42 which is spaced slightly from the shoulder 38 to provide an intervening chamber 44.

The chamber 44 provides a space into which the tucked in portion of the wrapper which closes the adjacent end of the cartridge body may extend as the powder is subjected to pressure to force it from the device, as is illustrated at 26' in 45 Figure 4 of the drawing.

The contracted neck portion 42 serves to prevent too rapid movement of the powder through the discharge passage of the member 16, thereby 50 insuring that the powder is discharged more in the form of a continuous spray than a single blast. This is also aided by reason of the projection of the adjacent tucked in portion of the cartridge wrapper into the chamber 44 under very 55 light pressure upon the powder, therefore permitting movement of the powder before sufficient pressure is built up to discharge the powder in a single blast-like charge.

From the contracted neck portion 42, the discharge passage is flared outwardly as at 48 to 60 provide a relatively large discharge opening 50 which permits the powder to discharge in a spray-like form as illustrated in Figure 4 of the drawing.

The form of the invention illustrated in Figure 8 of the drawing provides for opening both ends of the cartridge when the two members of the insertible head are threaded together and to this end, the end wall of the recess in the member 16 is so constructed as to provide a conically shaped projection 60, which forces the adjacent tucked in portion of the wrapper inwardly of the

cartridge body as the two members of the insertible head are threaded together, thus automatically opening both ends of the cartridge as illustrated in Figure 8, when the device is assembled for use.

From the foregoing it will be apparent that the present invention provides a new and novel construction by which each of the recited objects are accomplished, and while the invention has been herein illustrated in its preferred forms, 10 it is to be understood that it is not to be limited to the specific construction herein set forth, but may be embodied in other forms within the scope of the appended claims.

Having thus described the invention, what is 15 claimed as new, is:

1. In a device of the character described, an insertible head comprising two hollow members separably connected together to provide a cartridge receiving chamber, a projection extending 20 into said chamber from one end thereof, the other end of the chamber having a discharge passage contracted intermediate its ends to provide an intervening chamber immediately adjacent the end of the cartridge chamber into 25 which the adjacent end of a cartridge may expand, and a shoulder at each end of the cartridge chamber for engagement by the cartridge to prevent endwise movement of a cartridge in the cartridge chamber.

2. In a device of the character described, an insertible head member for body cavities comprising two hollow members each having a longitudinally extending passage, means for securing said hollow members together to combine in providing a cartridge receiving chamber having an inlet passage and an outlet passage, means adapted to hold a cartridge against longitudinal movement in said chamber when said members are secured together in their operative position, and means for rupturing one end of said cartridge during relative movement of the members to their connected position.

3. In a device of the character described, an insertible head member for body cavities comprising two hollow members separably connected together, said hollow members when connected together providing a chamber for receiving a cartridge having disruptible ends, each end of said chamber comprising a longitudinally extending 50 conical projection having a base substantially co-extensive with the end of the chamber for engaging and rupturing the ends of a cartridge placed in the chamber, said projections having central passages communicating with the chamber, the passage in one of the projections being utilized for discharging the contents of the cartridge by fluid pressure admitted through the passage in the other of the projections.

4. In a device of the character described, an insertible head comprising two hollow members, means for securing said members together to provide a cartridge receiving chamber having inlet and outlet passages, said outlet passage being flared, means for holding a cartridge in the chamber when said members are secured together in their operative position and means extending into the chamber from the inlet passage for rupturing one of the ends of the cartridge when the members are secured together.

BROWN BOLTE.
